UNITED STATES PATENT OFFICE.

HOWARD T. HAMER, OF NARBERTH, PENNSYLVANIA.

COMBINATION CARPENTER'S GAUGE.

Application filed March 1, 1927. Serial No. 171,753.

My invention relates to new and useful improvements in a combination carpenter's gauge, and has for its primary object to provide in such a tool, a butt gauge that will 5 increase the accuracy of the work as laid out by the mechanic.

Another object of the invention is to provide a unique butt gauge marker, whereby either one of two points may be held in any 10 adjusted position by a single set screw.

A further object of the invention is to provide a rule adjustably mounted on the tool body which with the latter may be used as a square.

15 A still further object of the invention is to provide an angle block for detachable connection with the tool body and cooperating with the rule so that the latter may be used as a triangle.

20 Another object of the invention is to provide a guide member slidably mounted on the tool body and carrying a marker traveling along the line parallel with the outer edge of the rule for scribing a line at a distance from the rule parallel with its outer edge.

With these and other ends in view, this 25 invention consists in the details of construction and combination of elements herein-after set forth and then specifically designated by the claims.

In order that those skilled in the art to 30 which this invention appertains, may understand how to make and use the same, I will describe its construction in detail, referring by numerals to the accompanying drawings forming a part of this application, in which:

Fig. 1, is a perspective view of my improved combination carpenter's gauge, with 35 portions broken away to illustrate details of construction.

Fig. 2, is an enlarged perspective view of the sliding marker.

Fig. 3, is a fragmentary sectional view on 40 the line 3-3 of Fig. 1.

Fig. 4, is an enlarged perspective view of the butt gauge marker; and

Fig. 5, is a fragmentary perspective view 45 of a piece of work on which the tool may be used when marking building trim.

In carrying out my invention as herein embodied, 10 represents the body of the tool or gauge having flanges 11 projecting from two opposite sides of the body at both ends thereof, so that in effect the body and its flanges form an H-shaped tool.

Through the body longitudinally thereof, extends a hole 12 in which are mounted the semi-circular coacting butt gauge markers 13 and 14, each having at one end a barb or point 15, and when the two markers are in cooperative relation, as shown in Fig. 4, said points or barbs are at opposite ends. One of the markers, as 14, is provided with a longitudinal slot 16 for registration with the shank of a set screw 17, which extends through a longitudinal slot 18 in the tool body, and has threaded connection with the other marker 13.

From the foregoing, it will be noted that 70 when the set screw is screwed home, it will bind upon the tool body in the region of the slot 18 and draw the marker 13 toward the marker 14, and both of them toward one side of the hole 12, so as to clamp both the 75 markers in any adjusted position relative to each other and to the tool body. When it is desired to use the marker 14, the marker 13 must be sheathed within the tool body, thereby permitting said marker 14 to be 80 withdrawn a distance equal to the length of its slot 16, and likewise, when it is desired to use the marker 13, the marker 14 is replaced, which will then permit the withdrawal of the marker 13.

In using either of the butt gauge markers 85 they are withdrawn a distance equal to the cut to be made, which is indicated by the graduations 19, and then by moving the tool over an adjacent surface of the work, with 90 one of the flanges in contact with such surface, a mark will be produced by the point or barb 15.

In one of the flanges, is a slot 20 for the reception of the rule 21 having one edge projecting a suitable distance beyond the outer face of such flange, and said rule is provided with a longitudinal groove 22 into which projects the hook 23 of the rod 24, the latter passing through a suitable opening in the flange, and then along the outside of the tool body, and then through a pair of spaced lugs 25, between which is mounted the thumb nut 26 having threaded engagement with the rod 24 so that after the rule has been adjusted to any desired position, the turning 100 of the thumb nut 26 will bind the hook 23 into the rule, and thus hold said rule in the adjusted position.

On a flange adjacent the rule is mounted 110 a slide 27, one face of which is parallel with the longitudinal edges of the rule and sub-

stantially the same distance from the flange as the outer long edge of the rule, and said slide is held in any adjusted position by a set screw 28, passing through the slide and threaded into the flange on which the slide is mounted. This slide is provided with a longitudinal dovetail slot 29 for the reception of the tongue 30 of the marker 31, which also includes a finger piece 32 and a stylus 33.

To use the last described portion of the invention which is particularly adapted for marking building trim prior to being sawed by the mechanics, a length of the trim 34 is laid in place with one end fitting against the wall or other object, where it is to be fastened, while the other end overlaps a piece of the door frame 35 or other object, as shown in Fig. 5. Then by placing the tool so that the lower edge of the body rests upon the upper edge of the trim and the outer edge of the rule against a face of the object 35, the marker 31 may be moved up and down so as to scribe a line on the outer face of the trim 34 parallel with the face of the object 35 against which the rule is resting, so that when the trim is sawed, it will accurately fit against the object 35.

In order to provide for angular work, an angle block 36 is removably mounted upon an edge of the tool body and is provided with an arm 37 disposed on one side of the tool body with an aperture for the passage of a set screw 38 threaded into said body and said angle block has a slot 39 for registration with the rule 21. When in use, the gauge may be placed against the work to be marked with the hypotenuse of the angular block in contact with one edge of the work through setting the outer edge of the rule at an angle to said edge.

Of course I do not wish to be limited to the exact details of construction as herein shown as these may be varied within the limits of the appended claims without departing from the spirit of my invention.

Having thus fully described my invention, what I claim as new and useful is:

1. A tool comprising a body having flanges projecting in opposite directions therefrom; a rule slidably mounted in a slot in one of the flanges; a slide mounted on another of said flanges adjacent the rule; and a marker slidably mounted on the slide so as to parallel the outer edge of the rule.

2. A combination carpenter's gauge including a body having a pair of flanges at one end thereof projecting in opposite directions, one of said flanges having a slot therein; a rule mounted in said slot; means

to hold the rule in different adjusted positions; a slide mounted on the other flange; means to hold said slide in different adjusted positions; and a marker slidably mounted on the slide with its stylus element traveling along a line parallel to the outer edge of the rule.

3. The structure set forth in claim 2 wherein the means for holding the rule in different adjusted positions comprises a rod, a hook on one end of said rod engaging in a longitudinal groove in the rule, a pair of spaced lugs on the tool body through which said rod passes; and a thumb nut having threaded engagement with said rod and located between the lugs.

4. A combination carpenter's gauge including a tool body; a rule slidably mounted in said body; means to hold the rule in different adjusted positions; an angle hook having a bifurcated portion to straddle the rule; and means to detachably fasten said angle block on the tool body.

5. A tool including a tool body; a slide adjustable on a portion of said body and a marker mounted on the slide, said marker including a dovetail tongue for registration with a similar shaped groove in the slide; a finger piece; and a stylus, the latter overlying an edge of the slide and projecting beyond the inner face thereof.

6. A combination carpenter's gauge, comprising a tool body; oppositely projecting flanges at both ends thereof; a pair of co-acting semi-cylindrical markers slidably mounted in a hole through the body; means passing through a slot in the tool body and cooperating with the markers to hold them in different adjusted positions; a rule slidably mounted in one of the flanges at one end of the body; means to hold said rule in different adjusted positions; a slide mounted on the end of the flange adjacent the one in which the rule is mounted, said slide having a portion projecting from the outer face of the flange substantially the same distance as the outer edge of the rule projects from the face of its flange; means to hold said slide in different adjusted positions; a marker slidably mounted on said slide and having a portion disposed across the outer edge of said slide so as to travel in a line parallel with the outer edge of the rule; and an angle block removably mounted upon the tool body and coacting with the rule to form a triangle.

In testimony whereof, I have hereunto affixed my signature.

HOWARD T. HAMER.
